UNITED STATES PATENT OFFICE.

ABNER W. BISHOP, OF MIDDLEBURY, CUYAHOGA COUNTY, OHIO.

ANIMAL-POKE.

SPECIFICATION forming part of Letters Patent No. 352,175, dated November 9, 1886.

Application filed September 2, 1886. Serial No. 212,560. (No model.)

To all whom it may concern:

Be it known that I, ABNER W. BISHOP, of Middlebury township, in the county of Cuyahoga and State of Ohio, have invented a certain new and Improved Animal-Poke; and I do hereby declare that the following is a full, clear, and complete description thereof.

My invention consists of the means employed in attaching and securing the poke to the neck of the animal, the several parts being constructed and arranged as hereinafter described and shown in the following specification and drawings annexed, in which—

Figure 1 is a view of the poke, partly in section, parts being broken away. Fig. 2 is a side view. Fig. 3 is a section in the line x x , Fig. 1; and Fig. 4 is a detached section in line x' x' , Fig. 3.

Like letters of reference refer to like parts in the several views.

In the drawings, A, Figs. 1 and 2, represents the bow of the poke, to which is hinged the guard B, Figs. 1 and 3, by means of the staple or loop C, or its equivalent, which passes through the bow and is secured by screw-nuts a on the ends of the loop, as seen in Fig. 1. This loop embraces the bar D of the plate E, so that the guard is hinged to the bow at C. This guard B consists of two outer plates, E being the lower one and F the upper one, which plates are fastened together by means of rods or bolts G and studs G', or otherwise. Interposed between the two plates E and F is a block, H, as seen in Figs. 3 and 4. The rods 35 G, in passing from one plate to the other, extend through this block H, and are riveted down on the outside of the two plates. The studs G' aid in securing the plates together as they extend through from one plate to the other, and are headed down on the plates. The studs G' are provided with shoulders on which the inside of the plates are in contact for support at these points.

In the block H are tightly inserted the shanks 45 of the spear-points I, as seen in Fig. 4, each one being surrounded by a spiral spring, J, Fig. 3. The spear-points extend loosely through the slide K, which is so placed between the two plates E F as to move freely between them.

On the lower side of the slide is a shoulder,

L, Fig. 4, which extends the entire length of the slide. On the front of the plate E is a flange, M, which forms the entire front-edge length of the plate, and is adapted to the shoulder L of the slide as a stop when the slide is moved out by the action of the springs J.

It will be seen in Figs 3 and 4 that one end of the springs abuts against the block H, while the other end is in contact and pressing against the inside face of the slide K and holding it in the position to cover the spear-points, as seen in Fig. 4, with the shoulder L of the slide K in contact with and arrested by the flange M from any further projection of the slide from 65 between the plates.

When the poke is attached to the neck of the animal, the slide is then directly in front of the breast, with the spear-points not exposed, as shown in Fig. 4. On the beast attempting a breach, the arms of the bow are brought in contact with the obstruction opposed to the animal. The slide K is then forced back by the breast of the animal pressing the arm of the bow against the fence or wall at 70 attempted to be breached. This action uncovers the spear-points by the moving back of the slide, and presents the spear-points to the breast of the animal, pricking so sharply that it will at once recede. This backing of the 75 beast removes the pressure upon the slide, which will then move out and cover over the spear-points by the force of the springs J on the inside of the slide, thereby relieving the animal from the pricking of the spear-points. 85

From the end of the plate E extends a stem, N, Figs. 1 and 2, having at the free end a neck, a , with a collar or shoulder, b , at the end. The stem is of sufficient length to pass through the bow-arm and be locked by the slide-plate O. 90

In attaching the poke to the animal's neck the guard is turned down to the side of the arm. The arms are then spread apart on raising the guard to admit of the free end of the stem passing through the hole P, receiving the stem 95 therein, as seen in Fig. 1. The slide-plate O is attached to the side of one arm by means of screws or other devices in such way as to admit of the slide-plate moving in the line of the slot Q.

Equidistant from the ends of the slot Q is a circular opening, R, in which the inner ends

of the slots terminate. Around the stem of the screw S is a spiral spring, T, in the cavity of the poke-arm. One end of this spring is impinged against the under side of the plate O, while the opposite end is on the bottom of the cavity, as seen in Fig. 1.

In locking the guard to the poke on the animal's neck, the stem N is, as stated, passed through the hole P in the arm, and the collar *b* at the outer end passes through the opening R in the plate O, so that the neck *a* is in the opening in the plate, with the collar *b* on the outside. On sliding the plate down the neck *a* will enter the slot, as seen in Fig. 2, which will lock or fasten the guard to the poke, as the collar *b* is on the outside of the slide-plate with the neck in the slot; hence the guard cannot be separated from the bow without spreading the arms, and this cannot be done until the slide-plate is moved, so that the collar *a* will be in the circular opening R.

The slide-plate O may be so arranged in its

relation with the bow and its attachments as to be moved in either direction, for the purpose of locking the stem N to the bow. The spring T presses against the plate O with sufficient force to hold the plate in position when the collar and neck *a* are in the said plate.

What I claim as my invention, and desire to secure by Letters Patent, is—

The combination, with the poke-bow A and the guard B, hinged at one end thereof to one arm of the bow, and provided with a stem, N, at the opposite end, having a neck and collar to extend through the aperture P of the other arm of the bow, of the slotted plate O and spring T, arranged substantially as described, for the purpose set forth.

In testimony whereof I affix my signature in presence of two witnesses.

ABNER W. BISHOP.
